UNITED STATES PATENT OFFICE.

CANFIELD JOSEPH ROUSSEAU, OF NEW YORK, N. Y.

ROTARY EXPLOSION-ENGINE.

No. 858,912.

Specification of Letters Patent.

Patented July 2, 1907.

Application filed April 2, 1906. Serial No. 309,378.

To all whom it may concern:

Be it known that I, CANFIELD JOSEPH ROUSSEAU, a subject of the King of Great Britain, and a resident of the city of New York, borough of Manhattan, in the 5 county and State of New York, have invented a new and Improved Rotary Explosion-Engine, of which the following is a full, clear, and exact description.

The object of the invention is to provide a new and improved rotary explosion engine which is simple and 10 durable in construction, very effective in operation, and arranged to give a plurality of impulses to the rotator on every revolution thereof.

The invention consists of novel features and parts and combinations of the same which will be more fully 15 described hereinafter and then pointed out in the claims.

A practical embodiment of the invention is represented in the accompanying drawings forming a part of this specification, in which similar characters of reference indicate corresponding parts in both the views.

Figure 1 is a sectional side elevation of the improved engine, and Fig. 2 is a transverse section of the same on the line 2—2 of Fig. 1.

The cylinders A² A² of the engine are provided with 25 intersecting bores A', A⁴ in which are mounted to rotate a rotator B and an abutment C respectively. The rotator B is secured on a main shaft D journaled in suitable bearings arranged in the cylinder heads, and on the outer end of the shaft D is fastened a pulley D' or 30 a similar device for transmitting the rotary motion of the engine to other machinery. On the shaft D outside of the cylinder A is also secured a gear wheel E in mesh with a gear wheel E' secured on the outer end of a shaft F on which the abutment C is fastened, and 35 which shaft F is journaled in the heads of the cylinder A. The rotator B is provided with radially disposed sliding piston heads B' each mounted on a screw rod G and pressed on by a spring H to normally hold the piston head in an outermost position so that the outer end 40 of the piston head is in contact with the inner peripheral surface of the bore A'. The abutment C is provided with a plurality of compression chambers C' each having a flaring mouth C² leading to the peripheral face of the abutment C, as plainly illustrated in 45 Fig. 1, and the said chambers C' and their mouths C² are arranged to register with the piston heads B' when the engine is running. Each of the chambers C' is adapted to register with igniting devices I and I' held in recesses A³ formed on the inside of one of the cylinder heads, as plainly shown in Fig. 2, so that when the 50 engine is running and one of the chambers C' registers with the recess A³ containing the igniting device I or I' in active position, then an ignition of the compressed charge contained in the chamber C' takes place to act 55 on the piston head B' in register at a time with this chamber, to rotate the rotator B either in the direction

of the arrow a' or in the inverse direction thereof, according to which of the igniting devices I or I' is in active use at the time.

As shown in Fig. 2 the igniting device is in the form 60 of an electric plug, controlled in the usual manner by a suitable controlling device J from the main shaft D of the engine, so that the charge is ignited at a proper time by either of the igniting devices I, I'.

The bore A' is connected with pipes K and K', 65 either of which may be the admission pipe and the other the exhaust pipe: for instance, as shown in Fig. 1, the pipe K is the admission pipe for admitting the explosive mixture to the bore A', while the pipe K' is, for the time being, the exhaust pipe; but it is evident 70 that by suitable valve connections the pipe K' may be made the inlet pipe for the explosive mixture, while the pipe K then becomes the exhaust pipe.

The operation is as follows: The explosive mixture, 75 passing by the pipe K into the bore A', is carried by the advancing piston head B' along in the bore and into and through the mouth C² into the chamber C', then moving into register with the bore A'. Thus, as the piston head B' advances to finally pass into the mouth C² of this registering chamber C', it is evident that the 80 charge is compressed and confined within the chamber C', and, as the piston head B' now moves past its vertical center together with the filled chamber C' into the position shown in Fig. 1, it is evident that when an explosion now takes place the force exerted against this 85 piston head B' rotates the rotator B in the direction of the arrow a'. In the meantime, the next following piston head B' carries a charge along to force this charge into the next following chamber C' to compress and to confine it therein, the compressed charge being 90 finally ignited by the igniting device I immediately after this piston and the filled chamber C' in register with this piston have passed the vertical position, so that another impulse is given to the rotator B. Now, by having three piston heads B', as shown in the drawings, and corresponding chambers C', it is evident that 95 three successive impulses are given to the rotator B by each revolution thereof, and, consequently, a continuous and steady rotary motion is given to the shaft D and the machinery connected therewith. When it is desired 100 to reverse the engine the igniting device I is cut out and the igniting device I' is cut in, and the explosive charge is admitted to the bore A' by way of the pipe K' while the exhaust takes place by way of the pipe K. In this case the charge admitted into the bore A' is carried along by the advancing piston head and forced into the corresponding chamber C' to be compressed therein and finally exploded by the igniting device J after the piston has passed a vertical position to the right hand side, so that the rotator B is rotated in the inverse direction of the arrow a'. Each mouth C² is shaped to open 105 into the bore A' shortly after the advancing piston

head B' has passed the inlet pipe K or K', so that the compression of the charge is gradual by the advancing piston head, which latter closes the mouth C² of the filled chamber while passing from the vertical position 5 to the igniting position. It is understood that after the piston has received an impulse and passed the exhaust pipe K or K', then exhaust takes place through this pipe and any residue of burned gases left in the chamber C' is passed to the atmosphere through a suitable 10 exhaust port L or L' formed in the wall of the bore A².

From the foregoing it will be seen that the engine is very simple and durable in construction, is composed of comparatively few parts, not liable to get easily out of order, and the engine can be readily reversed. 15 It is understood that I do not limit myself to the number of piston heads B' and chambers C' employed, as the same may be varied without deviating from the spirit of my invention. 20

Having thus described my invention, I claim as new and desire to secure by Letters Patent:

1. A rotary explosion engine comprising cylinders having intersecting bores, a rotator in one of the bores and having piston heads, a revolute abutment adapted to rotate in the other bore and having a plurality of compression chambers into which the explosive charge is forced and compressed by the piston heads, and ignition devices for igniting the compressed charges in the said chambers. 25

2. A rotary explosion engine comprising cylinders having intersecting bores, a rotator in one of the bores and

having piston heads, a revolute abutment adapted to rotate in the other bore and having a plurality of compression chambers into which the explosive charge is forced and compressed by the piston heads, each chamber having a flaring mouth, and ignition devices for igniting the compressed charges in the said chambers. 3

3. A rotary explosion engine comprising cylinders having intersecting bores, a rotator in one of the bores and having piston heads, a revolute abutment adapted to rotate in the other bore and having a plurality of compression chambers into which the explosive charge is forced and compressed by the piston heads, ignition devices for igniting the compressed charges in the said chambers, and means for rotating the said rotator and the said abutment in unison. 40

4. A rotary explosion engine comprising cylinders having intersecting bores, a rotator mounted to rotate in one of the bores and provided with a plurality of slideable spring-pressed piston heads, a revolute abutment in the other bore of the cylinder and having in its peripheral face a plurality of compression chambers each provided with a flaring mouth, ignition devices, a source of electricity for the said igniting devices and arranged to make connection with an igniting device at the time a compression chamber moves into explosion position, and means for rotating the said rotator and the said abutment in unison. 45

In testimony whereof I have signed my name to this specification in the presence of two subscribing witnesses.

CANFIELD JOSEPH ROUSSEAU.
